COUPLER ATTACHMENT

Frank H. Kayler, Alliance, Ohio, assignor to
American Steel Foundries, Chicago, Ill., a corporation of New Jersey

Application December 6, 1946, Serial No. 714,436

20 Claims. (Cl. 213—12)

1
This invention relates to couplers and more particularly to a novel improved coupler construction for railway cars having cushion type underframes.

A specific object of my invention is to devise a novel connection between the coupler and the center sill of a railway car body underframe.

Another object of my invention is to provide such a connection between the coupler and the center sill as will permit lateral and vertical angling of the coupler relative to the center sill as well as reciprocal movement relative thereto.

A further object of my invention is to devise a combination striking casting and coupler support adaptable to be associated with a plurality of different types of couplers and incorporating upper and lower guides with vertical pin slots for reception of a vertical pin for securing one type of coupler and also side guides with horizontal key slots for reception of a horizontal key for securing another type of coupler.

The foregoing and other objects and advantages of the invention will become apparent from a consideration of the following specification and accompanying drawings, wherein:

Figure 1 is a top plan view, partly in section, showing a tightlock coupler associated with a center sill of a cushion type car body underframe and also illustrating the coupler carrier and an embodiment of one form of my invention, the section being taken in the horizontal plane indicated by line 1—1 of Figure 2.

Figure 2 is a sectional view of the assembly shown in Figure 1, the section being taken in the longitudinal vertical plane substantially as indicated by line 2—2 of Figure 1.

Figure 3 is a fragmentary vertical cross section of the assembly taken in the plane indicated by the line 3—3 of Figure 1.

Figure 4 is a fragmentary horizontal section of the assembly taken in the plane indicated by line 4—4 of Figure 2, the parts, however, being shown in buffed position.

Figures 5—7 illustrate my novel sliding bushing, Figure 5 being a top plan view thereof, Figure 6 being a front end elevation thereof, and Figure 7 being a side elevation thereof.

Figures 8—10 are fragmentary views of an assembly similar to that shown in Figure 1 and embodying another modification of my invention, Figure 8 being a fragmentary top plan view thereof, the center sill, however, being shown in horizontal section, Figure 9 being a sectional view thereof, the view being taken in the plane sub-

stantially as indicated by line 9—9 of Figure 8, and Figure 10 being a sectional view taken substantially as indicated by line 10—10 of Figure 8.

Figures 11—13 are fragmentary views of an assembly similar to that shown in Figure 1 and embodying still another modification of my invention, Figure 11 being a fragmentary view similar to that shown in Figure 2, Figure 12 being a sectional view thereof taken in the transverse vertical plane substantially as indicated by line 12—12 of Figure 11, and Figure 13 being a fragmentary bottom view thereof taken substantially in the plane indicated by line 13—13 of Figure 11.

Describing the invention in detail and referring first to Figures 1—7 inclusive, the invention is illustrated in connection with a vertically interlocked head type coupler as applied to a structure commonly known in the art as a cushion type car body underframe including a center sill 2 movable longitudinally relative to the car body underframe (not shown), said center sill being of channel-section and comprising the top wall 4 and the side walls 6 and 8 depending from said top wall at opposite sides thereof, said side walls merging with the outturned horizontal flanges 10, 10 integrally formed at the bottom edges thereof.

Encased in the center sill is a combination striking casting and coupler support 12 (Figure 2) having top and bottom webs 14 and 16 (Figure 2) and side webs 18 and 20 (Figure 1), said casting being secured to said center sill in any convenient manner as by rivets 22, 22.

The coupler (fragmentarily shown), generally designated 24, has a shank 26 projecting into the casting 12, said shank 26 being supported by a carrier, generally designated 28, comprising a housing 30 being an integral part of said casting 12 and housing the springs 32 (Figure 2) supporting a carrier plate 34 engaging the shank 26 to afford a resilient support therefor, the shank being slidable on said plate during horizontal and lateral angling and reciprocal movement of the shank.

The shank 26 adjacent the rear extremity thereof is provided with a pin opening 36 formed with the angularly arranged faces 37, 37 converging toward the rear extremity of said shank and providing a fulcrum for the pivot or coupler pin 38 extending through said opening 36, said opening 36 also receiving a pin bearing block 40 in complementary cylindrical face engagement as at 42 with the pin 38 and in arcuate face engagement as at 44 with the coupler shank, which is in spherical face engagement as at 46 (Figures 1 and 2) with the follower 48 along com-

plementary convex concave surfaces, said follower being supported by the transverse member 47 secured at opposite ends thereof as at 50, 50 to said flanges 10, 10, said follower being the forward portion of a draft appliance and is herein illustrated having a flat rear face abutting against the head of the rod 52 extending into the spring 54 in the housing 56 (Figure 2).

The top end of the pin 38 is received within the elongate slot 58 having a width such as will conveniently admit said end of said pin, said slot being formed in the upper coupler guide 60 integrally formed on the inner face of the top web 16 of the casting 12 adjacent the rear or inner end thereof.

The lower end of the pin 38 extends into the sliding bushing 62 substantially T-shaped in cross section (Figure 3). The top of the bushing bears as at 64 against the lower edge of the pin bearing block 40 and is provided with a flat surface adapted for engagement with a convex surface 66 formed on the bottom of the inner extremity of the shank. The top of block 40 abuts the adjacent face of the upper guide as at 68 (Figure 2) and is slidable thereon during reciprocal movement of said coupler as hereinafter described, said last-mentioned face also abutting the convex surface 67 formed on the top side of the inner extremity of said shank.

The bushing 62 is received in the elongate opening or slot 70 open at the rear end thereof, said slot 70 being provided in the lower coupler guide 72 formed on the inner face of the bottom web 16 of the casting 12 adjacent the inner end thereof, said opening 70 being vertically aligned with the heretofore described slot 58 in the upper guide 60. At opposite sides of the bushing 62 adjacent the top thereof are formed the integral outturned lips or flanges 74, 74 (Figure 6) riding as at 76 (Figure 3) on the bearing portions or ledges 78 of the guide 72, said ledges defining the opposite sides of the slot 70 and engaging the sides of said bushing. Depending from the bushing 62 at opposite sides thereof are the spaced legs or lugs 86, 86 merging with the arcuate front wall 82 on the bushing 62, said legs presenting the outturned shoulders 81, 81 extending transversely of said ledges 78, said shoulders with said flanges 74, 74 and ledges 78 forming a dovetailed or tongue and groove interlock, as may well be seen in Figure 3.

A retainer key or locking pin 84 extends through aligned openings 86, 86 in the lugs 80, 80 (Figure 5) and passes under the adjacent end of the coupler pin 38 and abuts thereagainst as at 88 for supporting said pin 38 and holding the same in assembled relation with the other parts of the assembly, as previously described.

It will be noted that I have provided a slidable universal connection between the coupler and the center sill such as will permit vertical and lateral angling and also limit reciprocal movement of the coupler relative to said center sill.

It will be observed that when the coupler angles toward the extreme lateral position, one of the abutment faces 90, 90 (Figure 1) formed on the rear face of the shank is adapted to engage and fulcrum on the respective complementary surface of the follower 48, compressing the draft appliance, said appliance urging the said coupler to normal operating position, as will readily be understood by those skilled in the art. When the coupler angles downwardly, the carrier 28 is compressed; the pin 38 and the bearing block 40, however, remain in substantially vertical position, said carrier upon release of the forces angling

the coupler downwardly, forcing the coupler upwardly into normal operating position. If the coupler is angled upwardly, the weight of the coupler itself will bring it down to normal operating position when the forces causing such angling are removed.

It may also be noted that the casting 12 has integrally formed on the adjacent faces of the side webs 18 and 20 the horizontally aligned side guides 102, 102 with horizontal slots 104, 104 therein aligned with the slots 106, 106 in the side walls 6 and 8 of the center sill in order to permit, for emergency repair, the application of a coupler (not shown) commonly known in the art as a rigid shank horizontal key coupler, said slots 106, 106 and 104, 104 being provided for reception of a cross key (not shown) for securing said shank.

Referring now to Figures 8-10 which illustrate an assembly embodying another modification of my invention, it will be noted that in general the assembly is similar to that described with the exception that the top end of the pin 110 (Figure 10) extends into a sliding bushing 112, said pin projecting through the opening 114 provided on the rear extremity of the shank 116 and engaging the bearing block 118 seated in said opening 114 as at 120, said shank abutting the follower 122 bearing against the draft gear, generally designated 124.

The sliding bushing 112 has an opening 126 into which the said upper end of the pin 110 extends, said bushing being received in an elongate slot 128 open at the rear end thereof and formed in the upper coupler guide 130, said guide being an integral part of the casting 132 which is substantially the same as that previously described.

The bushing 112 has substantially flat parallel sides providing a large bearing area and each side of the bushing is provided with spaced horizontal top and bottom flanges 134 and 136 receiving therebetween the adjacent horizontal flange 138 on guide 130, the flanges 138 defining the opposite sides of said slot 128. The top flanges 134 serve to keep the bushing 112 from dropping out of the slot 128, while the bottom flanges 136 are adaptable to take upward thrusts from the coupler shank by abutting against the under side of the horizontal flanges 138.

Figures 11-13 illustrate an assembly similar to that described and embodying another modification of my invention. The pivot pin 150 extends through the pivot opening 152 in the rear end of the shank 154 and into the elongate upper slot 156 (similar to slot 58, Figure 1) in the upper coupler guide 155. The pin 150 has a lug or support member 157 fixed thereto adjacent the lower end thereof, said support member extending radially of said pin and being horizontally disposed and supports as at 158 the pin bearing block 160 seated in said opening 152. The lower end of the pin 150 extends into the slot 162 provided in the lower coupler guide 164, said guides being an integral part of the striking casting 166, which is substantially the same as that previously described. The pin 150 rests on the plate 168, having the front end thereof projecting into the transverse channel or pocket 170 formed in the lug 172 depending from the bottom web 174 (Figure 12) of the casting 166 adjacent the front end of the slot 162. The rear end of the plate 168 rests on one side of the substantially square securing pin 176, extending through aligned openings 178 in the depending lugs 180 integrally formed on the bottom web 174 of the casting 166.

at opposite sides of the slot 162, said lugs 160 merging with the inturned ends or end flanges 182 and forming therewith the rear corners of the slot 162, said flanges 182 abutting the rear edge of the plate 168.

It is to be understood that I do not wish to be limited by the exact embodiments of the device shown which are merely by way of illustration and not limitation as various and other forms of the device will, of course, be apparent to those skilled in the art without departing from the spirit of the invention or the scope of the claims.

I claim:

1. In a device of the class described, a car body underframe including a center sill, a hollow member encased within said center sill and comprising a striking casting and coupler support, a coupler shank projecting into said member, spaced guides in said member embracing the inner end of said shank therebetween, arcuate surfaces on said inner end of said shank engaging said guides, and slidable universal coupling means securing said shank to said member and permitting angling of said shank in both vertical and horizontal directions, and allowing said shank to reciprocate within said member, said means comprising a vertically disposed pivot pin extending through an opening in said shank and having the opposite ends thereof received within vertically aligned slots in said guides, said slots being elongated in the direction of the length of said shank and permitting said pin to slide therein upon reciprocal movement of said shank in a direction inwardly and outwardly of said member, yieldable means abutting the inner end of said shank and limiting the inward movement thereof, a bushing sleeved over at least one end of said pin and received in the associated slot and slidable with said pin therein, and securing means extending through said bushing and seated against the adjacent end of said pin.

2. In a car coupler mounting, a car having a cushion type underframe including a center sill having a top wall and depending side walls at opposite sides of said top wall, flanges on said side walls extending laterally therefrom, a member comprising combined striking casting and coupler support including an upper striking portion, side portions depending at opposite sides of said upper portion, means securing said portions to said walls, a lower portion beneath said upper portion and connecting the lower ends of said side portions and defining therewith an opening, coupler guides integrally formed on the adjacent faces of said upper and lower portions, a coupler having a shank extending into said opening between said guides, slidable universal coupling means securing said shank to said combined striking casting and coupler support, said means including a pin extending through said shank and at opposite ends thereof projecting into slots formed in said guides, a bushing on at least one end of said pin and engaging the opposite sides of the associated slot, tongue and groove means on said bushing and the associated guide for maintaining said bushing within the slot therein, and means for supporting said pin.

3. In a device of the class described, a car body underframe including a center sill, a hollow member encased within said center sill and comprising a striking casting and coupler support, a coupler shank projecting into said member, spaced guides in said member embracing the inner end of said shank therebetween, arcuate

surfaces on said inner end of said shank engaging said guides, and slidable universal coupling means securing said shank to said member and permitting angling of said shank in both vertical and horizontal directions and allowing said shank

- 5 to reciprocate within said member, said means comprising a vertically disposed pivot pin extending through an opening in said shank and having the opposite ends thereof received within vertically aligned slots in said guides, said slots being elongated in the direction of the length of said shank and permitting said pin to slide therein upon reciprocal movement of said shank in a direction inwardly and outwardly of said member, yieldable means abutting the inner end of said shank and limiting the inward movement thereof, and bushings sleeved over the ends of said pin and received in said slots and slidable therein with said pin.
- 10 4. In a device of the class described, a car body underframe including a center sill, a hollow member encased within said center sill and comprising a combination striking casting and coupler support, a coupler shank projecting into said member, spaced guides in said member embracing the inner end of said shank therebetween, arcuate surfaces on said inner end of said shank engaging said guides, and slidable universal coupling means securing said shank to said member and permitting angling of said shank in both vertical and horizontal directions and allowing said shank to reciprocate within said member, said means comprising a vertically disposed pivot pin extending through an opening in said shank and having the opposite ends thereof received within vertically aligned slots in said guides, said slots being elongated in the direction of the length of said shank and permitting said pin to slide therein upon reciprocal movement of said shank in a direction inwardly and outwardly of said member, and yieldable means abutting the inner end of said shank and limiting the inward movement thereof, a bushing sleeved over at least one end of said pin and received in the associated slot and slidable with said pin therein, and securing means extending through said bushing and seated against the adjacent end of said pin.
- 15 5. In a coupler arrangement, a vehicle having a cushion type underframe with a center sill, a hollow member mounted in said center sill and including upper and lower coupler guides therewithin, a coupler having a shank extending into said member between said guides, a pin extending through an opening in said shank and having its opposite ends projecting into elongate slots provided in said guides, a pin bearing block in said opening interposed between one side of said pin and the rear of said opening and projecting above and below said opening and seated at the top thereof against said upper guide, a member secured to said pin affording a seat for the bottom of said block, supporting means for said pin, said supporting means including a supporting plate disposed against the lower end of said pin, a lug depending from said first-mentioned member and positioned adjacent the front end of said slot in said lower coupler guide, a transverse pocket in said lug receiving the front end of said plate, and means securing said plate to said first-mentioned member.
- 20 6. In a coupler arrangement, a car body having a cushion type underframe including a center sill, a hollow member mounted in said center sill and comprising a depending guide and an opposed upstanding guide therewithin, vertically aligned slots in said guides, a coupler having a shank extending into said member between said guides, a slidable universal connection between said member and shank and comprising a sub-

stantially vertical pin extending through a substantially vertical opening in said shank, said pin having its upper end projecting into said slot in said first-mentioned guide, a bushing sleeved over the lower end of said pin and positioned in said slot in said second-mentioned guide, slidable interlocking means on said bushing and said second-mentioned guide, said means including laterally extending flanges integrally formed on the sides of said bushing and seated on the top surfaces of the portions of said second-mentioned guide defining the opposite sides of the slot therein, and lugs depending from said bushing at opposite sides thereof and having shoulders extending laterally beneath the respective of said portions.

7. In a coupler arrangement, a car body having a cushion type underframe including a center sill, a hollow member mounted in said center sill and comprising a depending guide and an opposed upstanding guide therewithin each having a slot in vertical alignment with each other, a coupler having a shank extending into said member between said guides, a slidable universal connection between said member and shank and comprising a substantially vertical pin extending through a vertical opening in said shank, said pin having its upper end projecting into said slot in said first-mentioned guide, a bushing sleeved over the lower end of said pin and positioned in said slot in said second-mentioned guide, and a tongue and groove interlock between said bushing and the portions of said second-mentioned guide defining the opposite sides of the slot therein, spaced depending lugs on said bushing, and a retaining key extending through said lugs and under said pin and affording support therefor.

8. In a coupler mounting, a car body having a cushion type underframe including a hollow center sill, a member comprising a striking casting and coupler support mounted in said center sill, a coupler having a shank extending into said member, an arrangement affording a slidable pivotal connection between said shank and member for permitting lateral angling and reciprocal movement of said coupler relative to said center sill and comprising a pivot pin extending through a substantially vertical opening in said shank, said pin at opposite ends thereof projecting into elongate slots in said member, said arrangement including an assembly permitting vertical angling of said coupler relative to said center sill and comprising a pin bearing block in said opening in complementary spherical face engagement at the rear extremity thereof with said shank and in complementary cylindrical engagement at the front thereof with said pin, and a substantially horizontal fulcrum in said opening intermediate the ends thereof providing a fulcrum for said shank against the adjacent side of said pin upon vertical angling of said coupler.

9. In a car coupler mounting, a combined striker casting and car coupler support adaptable to support a plurality of different types of couplers and comprising an upper striking portion and side portions depending at opposite sides of said upper portion, said portions being adapted to be secured to a center sill of a cushion type underframe of a car, a spring support portion beneath said upper portion connecting the lower ends of said side portions and comprising a housing, resilient means in said housing, and a vertically movable carrier member extending within said housing and seated on said resilient means and adaptable to support a coupler shank extend-

ing into said casting, said side portions having guides with horizontal key slots therein for reception of securing means for securing one type of coupler, said upper and spring support portions having coupler guides with vertical slots for reception of different securing means for securing another type of coupler.

10. In a coupler arrangement, a car body having a center sill movable longitudinally relative thereto, a hollow member mounted in said center sill and having top and bottom webs, opposed coupler guides integrally formed on the adjacent faces of said webs, elongate slots in said guides, bushings in said slots each being slidable within the associated slot and interlocked with the associated guide, a coupler having a shank extending between said guides, a slidable universal connection between said shank and member for permitting lateral and vertical angling and reciprocal movement of said coupler relative to said center sill, said connection including a pin extending through an opening in said shank and having the oposite ends thereof projecting into said bushings, and means associated with one of said bushings and said pin for maintaining the latter in assembled relation with said bushings and shank.

11. In a coupler mounting, a coupler shank, an element in spherical face engagement with the rear end of said shank and associated with draft means, a member encasing said shank and in abutment with said element, a car body carrying said member, a substantially vertical pin extending through an opening in said shank and projecting at opposite ends thereof into vertically aligned slots in said member and operatively connected thereto in the slots therein and slidable in said slots and affording a slidble pivotal connection between said shank and member, a pin bearing block in said opening and in cylindrical face engagement and spherical face engagement at opposite ends thereof with said pin and shank respectively, and permitting vertical angling of said shank relative to said member, and spaced means at opposite sides of said shank adapted for engagement with said element during extreme horizontal angling of said shank.

12. In a coupler arrangement, a car body having a cushion type underframe including a center sill, a hollow member mounted in said center sill and comprising a depending guide and an opposed upstanding guide therewithin each having a slot in vertical alignment with each other, a coupler having a shank extending into said member between said guides, a slidable universal connection between said member and shank and comprising a substantially vertical pin extending through a vertical opening in said shank, said pin having its upper end projecting into said slot in said first-mentioned guide, a bushing sleeved over the lower end of said pin and positioned in said slot in said second-mentioned guide, and slidable interlocking means on said bushing and said second-mentioned guide.

13. In a coupler arrangement, a car body having a cushion type underframe including a center sill, a hollow member mounted in said center sill and comprising a depending guide and an opposed upstanding guide therewithin each having a slot in vertical alignment with each other, a coupler having a shank extending into said member between said guides, a slidable universal connection between said member and shank and comprising a substantially vertical pin extending through a vertical opening in said shank, said pin having

one end projecting into one of said slots, a bushing sleeved over the other end of said pin and positioned in the other of said slots, slidable interlocking means on said bushing and the associated guide, and means for supporting said pin.

14. In a coupler mounting, a car body having a center sill, a member mounted in said center sill and comprising top and bottom webs and spaced side webs extending between and connecting said top and bottom webs and defining therewith an opening, coupler guides formed on the adjacent faces of said top and bottom webs and projecting into said opening, vertically aligned elongate slots in said guides, a coupler having a shank extending into said opening between said guides, and a slidable universal connection between said member and shank, said connection including a pivot pin extending through an opening in said shank and having its ends projecting into said slots and retaining means for holding said pin in assembled relation with said guides and shank.

15. In a coupler mounting, a car body having an underframe with a center sill movable relative thereto, a box-section member connected to said center sill and comprising top and bottom webs and spaced side webs extending therebetween, coupler guides integrally formed on adjacent faces of said top and bottom webs and disposed adjacent the rear extremity of said member, elongate slots in said guides, a coupler having a shank projecting into said member between said guides and having arcuate faces for engagement with said guides, and a slidable universal connection between said shank and member, said connection including a pin extending through an opening in said shank and into said slots at opposite ends thereof, and securing means for maintaining said pin in said opening and slots.

16. In a coupler arrangement, a vehicle having a cushion type underframe with a center sill, a hollow member mounted in said center sill and including upper and lower coupler guides therewithin, a coupler having a shank extending into said member between said guides, a pin extending through an opening in said shank and having its opposite ends projecting into elongate slots provided in said guides, a pin bearing block in said opening interposed between one side of

said pin and the rear of said opening and projecting above and below said opening and seated at the top thereof against said upper guide, a member secured to said pin affording a seat for the bottom of said block, and supporting means for said pin.

17. A device for connecting a coupler to an associated vehicle body comprising a hollow member carried by the body and comprising top and bottom walls, opposed pin slots in said walls, a bushing in one of said slots having tongue and groove engagement with the associated wall, a pin extending through said bushing and the other slot, means on said bushing supporting said pin, and a coupler shank pivotally connected to said pin, said slots being elongated to accommodate movement of said pin and bushing under buffing forces applied to said shank.

18. In a coupler mounting, a car body having an underframe including a hollow center sill, a member comprising a combination striking casting and coupler support mounted in said center sill, a coupler having a shank extending into said member, a pin extending through an opening in said shank and having its ends operatively associated with slots in said member and providing a slidable pivotal connection between said member and shank, said connection permitting substantially horizontal reciprocal movement of said coupler relative to said center sill.

19. In a coupler mounting, a car body having an underframe including a hollow center sill, a member comprising a combination striking casting and coupler support mounted in said center sill, a coupler having a shank extending into said member, and a slidable universal connection between said shank and said member permitting lateral and vertical angling of said coupler and reciprocal movement of said coupler longitudinally with respect to said member.

20. In a device of the class described, a sliding coupler pin bushing having channel guideways at opposite sides thereof, a relatively flat top surface, a vertical pin opening adaptable to receive a coupler pin therethrough, and depending lugs at opposite sides of said bushing with aligned openings for reception of a key for supporting said pin thereon.

FRANK H. KAYLER.
